UNITED STATES PATENT OFFICE.

PHILIP W. STONE, OF BOSTON, MASSACHUSETTS.

RAZORLIKE TOILET ARTICLE.

Application filed July 12, 1923. Serial No. 651,161.

This invention relates to toilet articles and while some of its features are of more general application, it is herein shown as embodied in a device for use in trimming calli and corns. For these uses it is important not only to provide a razor that is safely guarded against such use as might effect injury, but also to provide for getting at the seat or base of a corn or callus and so trimming the affected area as to relieve the pressure over the sensitive area and facilitate the healing of the same. With these and other objects in view this invention provides a safely guarded trimming device presenting an acting edge so concavo-convexed as to adapt it for scooping out a corn or callus from the foot, including approximately plane surfaces on the bottom of the foot as well as the more common convex surfaces.

A particular feature of this invention consists in the combination of a blade and its holder, including a guard, so formed and arranged as to allow the blade to dig and to guard against digging too deeply. In the illustrated embodiment the blade is of spring steel and is sprung out of its normal position to present a curved cutting edge. It is maintained in its sprung condition in bowed form by the construction and arrangement of the holder, which, further, is formed and arranged to include a guard to prevent the convexed blade from digging in too deeply.

A further feature of the invention consists in the described economically efficient method of manufacturing and assembling the described razor.

These and other features of the invention will be clear from the following description, taken in connection with the accompanying drawings and will be pointed out in the claims.

Fig. 1 of the drawings is a plan view of the blank used in the preferred method of manufacturing the illustrated blade holder, the line on which the blank is to be folded being indicated by broken lines, and the blade being shown in dotted lines in the relation it will occupy relatively to the holder.

Fig. 2 is a perspective view of the completed article.

Fig. 3 is a central transverse section through the holder and blade, the scale being enlarged.

Fig. 4 is a perspective fragmentary view to illustrate on an enlarged scale the rela-

tive formation of the parts in the preferred embodiment of the invention.

Fig. 5 illustrates a use of the razor.

The illustrated razor comprises a one piece holder and a blade B of spring steel. The holder is formed from a blank of sheet material, preferably of metal, adapted to be die-died out and formed by punching and pressing. As shown in Fig. 1, it presents the handle members 10, 10, the blade clamping members 12, 12, the blade eye 14 having the offset 25 pressed therefrom to form a guiding ledge, the back stop 15, which may be in duplicate and is capable of locating the blade in different positions of adjustment, if desired, the spanning member 16 having the locking tongue 18 notched at 19, and the locking recesses 20, 20 for cooperation with the tongue 18, 20.

The blank is first folded on the broken median line to form the handle and the blade clamp 12, 12 between the members of which the blade B is inserted and positioned against the back stop 15. A bend is then made at the junction of the spanning member 16 with the clamping member which carries the back stop. It is to be noted as important that the spanning member 16 is shorter than the blade clamping members so that as the spanning member is carried over the blade clamping members in assembling the razor it is necessary to bow the blade clamping members, as shown, in order to bring the tongue 18 opposite the locking recesses 20, 20. The notch 19 is formed out of alignment with the locking recesses, requiring that spanning member 16 be sprung downward to effect entrance of tongue 18 into the locking recesses 20, 20, after which the tongue springs upward of its own resilience to effect secure interlocking engagement of the notched portion of the tongue with the upper edge walls of the recesses.

As thus assembled the spanning member constitutes a chord joining the two ends of the arc into which the resilient blade clamping members are bowed. The bending of members 12, 12 with the blade between them not only forms the blade into the desired convex form for getting the cutting action desired, but clamps the blade securely between members 12, 12. Before assembling, the upper clamping member 12, having the offset 25, is preferably beveled or backed off. This offset 25 constitutes a suitable guide, in combination with the blade, to determine the normal cutting action of the

105

110

razor. This plane, established by the offset 25 and the edge of blade B, see Fig. 4, is usually adequate and safe for the starting cut to trim a callus or corn. The inclination can 5 be varied during progress of the cut to scoop out the heart of a corn by pressing the guiding face 25 into or raising it from the flesh. The concavity in the front edge of the spanning member aids vision of the working 10 point. The folded edge at the junction of members 12, 12 protects against injury by the razor, while the curvature of the bowed cutting edge enables the desired scooping action 15 to be obtained as distinguished from the action of a straight edged blade.

Having explained the nature of the invention and described a preferred embodiment thereof, I claim as new and intend to secure by Letters Patent all the novelty herein disclosed 20 and desire that the following clauses shall be interpreted to give effect to this purpose:

1. In a toilet article, the combination of a curved razor blade and its holder, including 25 a guide for the cutting edge of the blade, said guide being spaced below and located back of said edge to establish the plane of cutting action of the blade.

2. In a toilet article, the combination of 30 a blade curved transversely of its plane and a holder therefor, including a guide spaced below and located back of the edge of the blade to limit the depth to which the curved blade will enter upon its cut.

3. In a razor, a blade of spring steel 35 sprung lengthwise out of its normal shape, and means arranged as a chord over the spring blades to hold it so sprung.

4. In a razor, a blade of spring steel 40 sprung lengthwise into bowed shape by

bringing its ends closer together than their normal position a guard, and means arranged as a chord over the bowed blade and guard and serving to hold them in bowed condition. 45

5. In a razor, a blade curved lengthwise in the direction of its edge and a holder including means similarly curved and guarding the blade, together with means extending in the general direction of the blade and serving as a handle by which to manipulate the blade. 50

6. In a razor, a blade and a blade holder comprising a short member and a longer member, the ends of said two members being 55 connected together to maintain the longer member in bowed shape, the blade being carried by and conforming to the bowed shape of the longer member of the holder.

7. In a razor, in combination, a handle, a 60 blade, a blade clamp, a spanner shorter than the blade clamp extending lengthwise over and connecting the two ends of the clamp, and means to hold the clamp and the spanner in assembled relation with the blade 65 in bowed condition.

8. In a razor, a holder comprising a stamping folded longitudinally to form a handle and a blade clamp and having an end extension shorter than the clamp and folded back 70 over the clamp and secured to hold a blade in bowed condition.

9. In a razor, a holder comprising a stamping folded longitudinally to form a handle and a blade clamp and having an 75 end extension folded back over the clamp and secured to hold a blade.

In testimony whereof I have signed my name to this specification.

PHILIP W. STONE.
